SUCTION CLEANING APPARATUS

John H. Ashbaugh, Springfield, Mass., assignor to Westinghouse Electric & Manufacturing Company, East Pittsburgh, Pa., a corporation of Pennsylvania

Application July 20, 1938, Serial No. 220,223

8 Claims. (Cl. 15—8)

My invention relates to suction cleaners and has for an object to provide improved apparatus of this kind.

A further object of the invention is to provide improved means for adjusting the rotating brush of a cleaner for floor coverings.

A further object of the invention is to provide improved suction cleaning apparatus having a rotatable element that engages the surface being cleaned wherein the element may be readily adjusted relative its support without removing the element from the cleaning apparatus.

A still further object of the invention is to provide an improved adjustable rotating brush structure for a suction cleaner having indicia for indicating the position to which the brush is adjusted.

These and other objects are effected by my invention as will be apparent from the following description and claims taken in connection with the accompanying drawing forming a part of this application, in which:

Fig. 1 is a sectional view through a portion of a suction cleaner nozzle having a rotatable brush structure therein constructed and arranged in accordance with the invention;

Fig. 2 is a section taken along the line II—II of Fig. 1; and,

Figs. 3 and 4 are side and end views respectively of the bearing member shown in Fig. 1.

Reference will now be had to the drawing wherein I have shown a portion of a conventional suction cleaner nozzle at 10 having a rotatable brush 11 disposed therein and actuated in any well-known manner such as, for example, by the suction creating apparatus (not shown). The opposite end of the nozzle 10 and brush 11 are not shown as the construction thereof is similar to the end shown. The nozzle 10 is provided at its bottom with lips 12 that engage the floor covering to be cleaned and which encompass an inlet opening 13 for air translated through the nozzle. The brush 11 includes a plurality of bristles 14 that normally extend slightly below the plane of the lips 12 and sweep the surface being cleaned clear of material that adheres thereto as is well understood. The brush 11 is provided with a journal 15 that is supported by a bearing structure, generally indicated at 16 and constructed in accordance with my invention.

During operation of a brush of the type shown at 11, the ends of the bristles 14 become worn so that the brush does not make proper contact with the floor covering to effectively sweep material therefrom. Accordingly, it becomes neces-

sary to adjust the brush structure 11 downwardly in order to obtain proper contact between the bristles 14 and the floor covering. The adjustment of the brush upwardly and downwardly is effected by the adjustable bearing structure 16 to be described hereinafter. When the brush 11 is new, the bearing structure is adjusted to its most elevated position and, as the brush becomes worn, the bearing structure is periodically adjusted to lower the brush 11. The adjustable bearing structure 16 includes a bearing member 17, preferably polygonal in cross section, as best shown in Figs. 2 and 4 where it is supported from the nozzle 10. In the embodiment shown, the bearing member is hexagonal in cross-section for providing six faces 18 on the exterior thereof, the faces 18 being spaced uniformly from the center of the bearing member 17 and the brush journal 15 being eccentrically disposed with respect to the center of the bearing member 17, as best shown in Fig. 4.

Support for the bearing member 17 is provided within the nozzle 10 by means of a pair of flat springs 19 that are secured to the nozzle 10 by means of a screw 21. The springs 19 bear against opposed sides 18 of the bearing member 17 and are preferably provided with inwardly extending portions 22 which prevent downward movement of the bearing 17 in service. Upward movement of the bearing 17 is prevented by the screw 21.

Adjustment of the brush 11 upwardly and downwardly is effected by rotating the bearing member 17 within its resilient support. As the center of the bearing member 17 is maintained in a fixed position relative the nozzle 10, it will be apparent that the journal 15 which is eccentrically disposed with respect to the center of the bearing member 18, will be raised or lowered depending upon which direction the bearing member 17 is rotated. In the position shown, the bearing member 17 is adjusted so that the journal 15 of the brush is in its most elevated position, or the position occupied when the brush is new. Rotation of the bearing member 17 clockwise to bring the next succeeding faces 18 into engagement with the springs 19 will effect a downward movement of the brush 11, which operation is effected when the brush has been worn sufficiently to require adjustment. It will be apparent that the hexagonal bearing member 17 provides for four positions of the brush 11.

In order to facilitate rotation of the bearing member 17, a plurality of recesses or slots 23 are formed on the exterior thereof for receiving a suitable tool such as, for example, a screw driver, which may be inserted through the inlet 55

opening 13 of the nozzle 10. After inserting the tool in a recess 23, it is moved to effect a rotary movement of the bearing member 17, at which time the springs 19 flex to permit the corners intermediate the faces 18 to pass. The springs 19 then move inwardly to engage the next succeeding pair of faces 18. Indicia indicated at 24, such as, for example, the numerals 1 to 4, may be provided on the outer surface of the bearing member 17 for indicating the position to which it has been adjusted. In this connection, it will be understood that the bearings at both ends of the brush 11 should be adjusted to the same index. The resilient springs 19 for supporting the bearing member 17 readily permit insertion and removal of the brush and bearing 17 from the nozzle 10 when desired.

From the foregoing description, it will be apparent that I have provided improved means for adjusting the rotatable brush of a cleaner for floor coverings that may be readily adjusted without removal of the brush from the apparatus. Furthermore, the brush may be readily removed from the apparatus if desired, for cleaning or replacement.

While I have shown my invention in but one form, it will be obvious to those skilled in the art that it is not so limited, but is susceptible of various changes and modifications without departing from the spirit thereof, and I desire, therefore, that only such limitations shall be placed thereupon as are imposed by the prior art or as are specifically set forth in the appended claims.

What I claim is:

1. In suction cleaning apparatus, the combination of a nozzle, a rotatable element disposed therein for engaging the surface to be cleaned, a member polygonal in cross-section and having a plurality of sides, said member being provided with a bearing in which the rotatable element is journaled, said bearing being eccentrically disposed with respect to the axis of the member, and resilient means carried by the nozzle and engaging at least one of the sides of the member forming the polygon for supporting the member in the nozzle, said means affording rotary movement of the member about its center while supporting the same, whereby the axis of the rotatable element is adjustable toward the mouth of the nozzle.

2. In suction cleaning apparatus, the combination of a nozzle, a rotatable element disposed therein for engaging the surface to be cleaned, a member polygonal in cross-section and having a plurality of sides, said member being provided with a bearing in which the rotatable element is journaled, said bearing being eccentrically disposed with respect to the axis of the member, resilient means carried by the nozzle and engaging at least one of the sides of the member forming the polygon for supporting the member in the nozzle, said means affording rotary movement of the member about its center while supporting the same, whereby the axis of the rotatable element is adjustable toward the mouth of the nozzle, and means arranged exteriorly of the member for receiving a tool employed in rotating the member during adjustment thereof, the parts being constructed and arranged so that a tool may be inserted through the mouth of the nozzle and rotate said member by engagement with said last-mentioned means.

3. In suction cleaning apparatus, the combination of a nozzle, a rotatable element disposed therein for engaging the surface to be cleaned,

a member polygonal in cross-section and having a plurality of sides uniformly spaced from the center of the member, said member being provided with a bearing in which said rotatable element is journaled, said bearing being eccentrically disposed with respect to the center of the member, and resilient means carried by the nozzle and engaging opposite sides of the member which form the polygon for supporting the member in the nozzle, said resilient means affording rotary movement of the member about its center without removing the member from the resilient means, whereby the axis of the rotatable element is adjustable toward the mouth of the nozzle.

4. In suction cleaning apparatus, the combination of a nozzle, a rotatable element disposed therein for engaging the surface to be cleaned, a member polygonal in cross-section and having a plurality of sides uniformly spaced from the center of the member, said member being provided with a bearing in which said rotatable element is journaled, said bearing being eccentrically disposed with respect to the center of the member, and resilient means carried by the nozzle and engaging opposite sides of the member which form the polygon for supporting the member in the nozzle, said resilient means affording rotary movement of the member about its center without removing the member from the resilient means, whereby the axis of the rotatable element is adjustable toward the mouth of the nozzle and said member having a plurality of slots formed on the exterior thereof for receiving a tool employed in adjusting the member, the parts being constructed and arranged so that a tool may be inserted through the mouth of the nozzle and the member rotated by engagement of said tool in one of said slots.

5. In suction cleaning apparatus, the combination of an air intake nozzle, a rotatable brush disposed in the inlet thereof, a member of polygonal cross-section and having a plurality of sides spaced substantially uniformly about the center of the member, a bearing in which the brush is journaled formed in the member and eccentrically disposed relative the center thereof, resilient means carried by the nozzle and engaging opposite sides of the member forming the polygon for supporting the member, said resilient means affording rotary movement of the member whereby the position of the brush and its bearing is adjustable toward the mouth of the nozzle, and said member having respective recesses associated with at least a portion of the sides thereof for receiving a tool employed in adjusting the member within its supporting resilient means, the parts being constructed and arranged so that such tool may be inserted through the mouth of the nozzle and the member adjusted by engagement of such tool in one of said recesses.

6. In suction cleaning apparatus, the combination of an air intake nozzle, a rotatable brush disposed in the inlet thereof, a member having a bearing portion eccentrically disposed with respect to the center of the member and in which the brush is journaled, and spring clip means secured to the interior of the nozzle and radially engaging opposite circumferential sides of the member for supporting the same therebetween and permitting rotary movement of the member while the same remains positioned by the spring clip means, the member and the spring clip means being formed with interlocking portions which yieldably retain the member against rotary movement.

movement in any one of a plurality of different rotary or angular positions, whereby the brush may be adjusted toward the exterior of the mouth of the nozzle.

5 7. Suction cleaning apparatus as set forth in claim 6, wherein said member and said nozzle are constructed and arranged so that a tool may be inserted through the mouth of the nozzle and engaged with said member and so that said member may be rotated without material translatory movement when so engaged by said screw driver.

10 8. In suction cleaning apparatus, the combination of an air intake nozzle, a rotatable brush disposed in the nozzle adjacent the mouth thereof, a member having a bearing portion in which the 15 brush is journaled, and means carried by said

nozzle for supporting said member, said supporting means permitting rotary movement of said bearing member about an axis parallel to but offset from the axis of said bearing portion without removing the member from the supporting means, said supporting means including spring means for yieldably retaining said member against rotary movement, said nozzle and said member being constructed and arranged so that a screw driver may be inserted through the mouth of the nozzle and engaged with said member and so that said member may be rotated by said screw driver when so engaged, whereby said brush may be adjusted toward the exterior of the mouth of the nozzle. 15

JOHN H. ASHBAUGH.
